UNITED STATES PATENT OFFICE.

RICHARD K. HOHMANN, OF BELVIDERE, ILLINOIS, ASSIGNOR TO NATIONAL SEWING MACHINE COMPANY, OF BELVIDERE, ILLINOIS, A CORPORATION OF ILLINOIS.

SEWING-MACHINE.

1,164,648.

Specification of Letters Patent. Patented Dec. 21, 1915.

Application filed July 6, 1914. Serial No. 849,083.

To all whom it may concern:

Be it known that I, RICHARD K. HOHMANN, a citizen of the United States, residing at Belvidere, in the county of Boone and 5 State of Illinois, have invented certain new and useful Improvements in Sewing-Machines, of which the following is a specification.

My invention relates to improvements in 10 sewing machines and has more particular reference to improvements in the take-up mechanism.

One of the objects of my invention is to provide an improved structure of this character which will be simple, durable and reliable in construction and effective and efficient in operation.

Other objects of my invention will appear hereinafter.

20 Referring to the accompanying drawings: Figure 1 is a view of the end of the sewing machine head with the end plate removed, the bed plate shown in section, and the take-up mechanism and shuttle shown in one of 25 their relative positions. Fig. 2 is a view similar to Fig. 1 showing the take-up and shuttle mechanisms in a different position. Figs. 3, 4, 5, 6, 7 and 8 are diagrammatic views showing various portions of take-up 30 mechanism at different points in the cycle of operation wherein a stitch is made.

It will be obvious to one skilled in the art, after having obtained an understanding of my invention from the disclosures herein 35 made, that my invention is capable of being variously modified and rearranged without departing from the scope and spirit of the invention, and I wish it so understood.

Referring more particularly to the drawings, I have indicated the bed plate of a sewing machine at 1, the head at 2 and the driving shaft, which is journaled in the head 2, at 3. I have not shown the connection between the head 2 and bed plate 1, or the driving means for the shaft 3 since these parts are of the ordinary construction and well known. Under the plate 1 is an oscillatory shuttle carrier 11, also of the usual construction and the details of which are not 45 shown. Riding in the shuttle carrier 11, and propelled by the turned portion 12 thereof, is a shuttle C of the usual construction and having flattened sides 19 and 20 adapted to slide against a guide, not shown, 50 to prevent rotation of the shuttle. The shut-

tle is provided with the usual sharp point adapted to enter the loop made up of portions D¹ and D² of the thread D, which is carried through the plate 1 in the usual manner by a needle 22 set in the end of a 60 needle bar 23.

In the structure shown I have indicated at 30 a feed bar for feeding the cloth. This may, of course, be of any suitable or standard construction and need not be particularly 65 described or shown. The free end of the arm 2 is enlarged in the usual manner to form a box or casing 31 for the take-up mechanism and other parts usual to sewing machines. This casing carries the usual 70 presser foot bar 32 which projects below the casing 31 and carries at its lower end the presser foot 33 which co-operates with the feed bar 30 to feed the cloth progressively with respect to the needle. This may 75 be of the ordinary construction and needs no further description. The needle bar 23, previously referred to, may also be of the ordinary construction having a suitable clamp or fastening device 34 at its lower 80 end for holding the needle 22. This needle bar is journaled at the upper and lower ends of the casing so that it may be reciprocated in a vertical line; that is, in a line perpendicular with respect to the line 85 of movement of the shuttle and also perpendicular with respect to the longitudinal axis of the shaft 3. In the construction shown the needle bar is positioned immediately in front of the end of the shaft 3 90 so that its longitudinal axis passes through the axis of the shaft 3. This needle bar derives its reciprocating movement from the shaft 3 through the medium of a crank member or disk 40 and a connecting link 41. 95 The connecting link is pivotally connected at its lower end 42 to the needle bar. At its upper end 43 it is pivotally connected to the crank member 40 so that the rotation of the crank member will rotate the upper 100 end 43 of the link and thereby reciprocate the needle bar. This crank member is enlarged at one side at 44 to provide a suitable counterweight to balance the rotating parts.

The take-up arm is also positioned within 105 the casing 31 and is operated by this mechanism. The eyelet end or free end 45 of the take-up arm 46 extends through a vertical slot 47 in the casing 31. This end of the take-up arm is reciprocated in a 110

substantially vertical plane and operates, as is well known, to draw the loop tight after the shuttle has passed through it and formed the stitch. The thread is brought from a spool, not shown, and passed through the thread check 48, main and auxiliary tension device 49, eyelet 50, thence through the eyelet end of the take-up arm as shown in Fig. 1, and thence down through the eye of the needle. The other or inner end of the take-up arm 46 is pivotally connected at 51 to the connecting link 41, as shown clearly in Figs. 1 and 2. It will be noted, however, that the connecting link or bar 41 is so formed that the pivotal point 51 of connection of the take-up arm with the link 41 is offset considerably with respect to a straight line drawn between the pivotal points in ends 43 and 42 of said connecting link 41. The take-up arm, as clearly shown in the drawings, extends in a substantially straight line from its pivotal point of connection 51 with the link 41 to a point 52 about midway of its ends and at this point 25 it is pivotally connected to one end of a curved link 53, the other end of which is pivotally connected at 54 to a fixed support, which in this case is the wall of the casing 31. From the pivotal point 52 the take-up 30 arm extends generally at an angle to the portion between the points 51 and 52.

In accordance with my invention the take-up arm operates in a certain timed relation to the movement of the shuttle but it does not move at a uniform speed like the shuttle does on account of the condition of the thread at various positions of the shuttle. When the shuttle enters the loop of thread brought down by the needle the take-up arm 35 will be in a position near the lower end of its stroke and continues to move downwardly until the tapering portion of the shuttle has passed through the loop of the thread, so that the take-up arm will exert 40 no pull on the thread while the shuttle is going through the loop. As soon as the shuttle passes the loop, however, the take-up arm will operate with a rather quick movement upwardly for the purpose of 45 drawing or pulling tight the loop which the shuttle made thereby to form the stitch.

In Figs. 3 to 8 I have illustrated in diagram the position of the parts of the take-up mechanism at various points in the cycle of operation thereof. In these diagrams the irregular dotted line 60 indicates the orbit in which the eyelet end of the take-up arm moves. The dotted line 61 indicates the elliptical orbit in which the pivotal point 55 51 moves, the dotted line 62 indicates the circular orbit in which the pivotal point of end 43 moves, and the straight line 63 indicates the line of movement of the pivotal point of end 42.

60 65 In Fig. 3, end 43 of connecting link 41 and

consequently needle 22, are at their lowest positions of movement and the shuttle C is at the very beginning of its forward movement, while eyelet 45 has yet a considerable part of its downward movement to be made. 70 Upon beginning the forward movement of the shuttle, and the upward movement of the needle corresponding thereto, see Fig. 4, the point of the shuttle enters loop D' of the thread and prevents the upward movement 75 of the needle from drawing the loop upwardly also. The eyelet 45 continues the downward movement through its positions shown in Figs. 4 and 5 and to a point just before it reaches its position indicated in 80 Fig. 6. This downward movement of the eyelet 45, after leaving its position in Fig. 3, loosens the thread sufficiently so that the entire shuttle may pass through the loop D' without placing the thread under tension. 85

In offsetting the point 51 of the connecting link 41, I provide means whereby the connecting link 41 passes its lower dead center in line 63 just before point 51, in its path 61, passes through a line passing through 90 points 51 and 52 in order to give a very slow motion to the eyelet 45 while the shuttle is passing through the loop D'. Fig. 5 diagrammatically illustrates the position of the take-up mechanism parts when the shuttle is 95 about half way through the loop of thread, and Fig. 6 illustrates said parts as the shuttle is practically through the loop.

The comparatively large size of the shuttle necessarily causes considerable excess thread 100 to be pulled from the spool in forming the loop large enough to allow the shuttle to pass through and as soon as the shuttle passes through the loop this excess must be drawn up tight to form a stitch. After 105 leaving the loop the shuttle has very little left to finish its stroke in the same direction and in consequence the excess of the loop must be quickly drawn up tight to form the stitch so that the shuttle on its return stroke 110 will not become entangled in the loop.

It will be seen that although the shuttle moves a very little distance in finishing its stroke the take-up mechanism carries the end 115 45 of the take-up arm upward with a quick motion substantially the entire length of its upward stroke thus quickly drawing the loop of thread tight.

Thus it will be seen that the shuttle mechanism and take-up mechanism are so related 120 and timed with respect to each other that the conditions of the thread at any point in the cycle of operation is properly taken care of by the take-up mechanism with the result that the stitches will be properly formed 125 even though the machine is run at a high speed.

What I claim is:

1. The combination of a shaft, a needle bar, a crank on said shaft, a connecting link 130

connected to said crank and said needle bar for reciprocating the needle bar, and a take-up arm having one end connected with the connecting link at a point intermediate the 5 ends of and offset from a straight line through the points of connection of the connecting link with the needle bar and crank.

2. The combination of a shaft, a crank on said shaft, a needle bar positioned to reciprocate in a line perpendicular to the longitudinal axis of said shaft, a connecting link between the crank and the needle bar for reciprocating the needle bar, a take-up arm having one end pivotally connected to said 10 connecting link at a point offset with respect to a straight line drawn through the points

of connection of said connecting link with the crank and the needle bar and having its other end adapted to oscillate, a fixed support, and a link pivotally connected at one 20 end to said support and at the other end to said take-up arm intermediate the ends of the latter.

In testimony whereof I have signed my name to this specification, in the presence of 25 two subscribing witnesses, on this 1st day of July, A. D. 1914.

RICHARD K. HOHMANN.
